2 SHEETS—SHEET 2.

UNITED STATES PATENT OFFICE.

ABRAM OSCAR HANCOCK, OF RICHMOND, VIRGINIA.

STOVE.

960,904.

Specification of Letters Patent. Patented June 7, 1910.

Application filed February 4, 1910. Serial No. 542,056.

To all whom it may concern:

Be it known that I, ABRAM OSCAR HANCOCK, a citizen of the United States of America, residing at Richmond, in the 5 county of Henrico and State of Virginia, have invented new and useful Improvements in Stoves, of which the following is a specification.

This invention relates to stoves, and has 10 for an object to provide a structure of this character which is capable of burning either wood or coal.

The particular object of the invention resides in the provision of a base member 15 which is constructed to form a permanent part of the structure and to provide a sheet metal drum member which is adapted for detachable engagement with the said permanent part of the structure thus providing 20 means whereby the said sheet metal part may be removed when worn or burned out and replaced at a minimum cost by a new part.

Another object of the invention is to provide 25 a hopper having vertical apertured walls spaced from the walls of the drum to provide a chamber and to so arrange or associate the said hopper with respect to the fire pot that communication is established 30 therebetween.

In the drawings, forming a portion of 35 this specification and in which like numerals of reference indicate similar parts in the several views:—Figure 1 is a vertical section through my improved stove. Fig. 2 is a horizontal section taken on the line 2—2 of Fig. 1. Fig. 3 is a detail perspective view 40 of the hopper. Fig. 4 is a detail partial vertical section taken on the line 4—4 of Fig. 1. Fig. 5 is a detail plan view of the fire pot. Fig. 6 is a detail plan view of the grate.

My improved stove as herein illustrated 45 consists preferably of a base member 1 which is of oval form preferably in horizontal section. This base member is provided with a bottom 2 on which is formed a series of suitably spaced ribs 3. The vertical wall of the said base member has formed 50 therein an opening 4 which is closed by a door 5 of any suitable form. This door is preferably provided with a damper 6 which may be of any approved well known construction. An ash tray 7 is supported upon 55 the ribs 3 of the bottom of the base member 1 and its construction permits it to be with-

drawn from the stove by way of the door opening 4. The base member 1, in practice, forms a permanent part of the structure and it is constructed preferably from cast-iron. 60 The said base member is mounted on suitable supporting legs 8, as shown.

The vertical wall of the base member 1 has formed thereon and upon its exterior surface a supporting rib 9 which receives the 65 lower edge portion of a sheet metal drum 10. This drum is provided with an opening 11 from which extends a short neck for receiving one end of a pipe connection 12 which is employed for the purpose of carrying off the waste products as is understood. 70 The drum is also formed to provide an opening 13 which is closed normally by a cap 14. This cap is interchangeable and may be engaged if desired with the flange which 75 extends from the opening 11. The flanged portion which extends from the opening 13 in the drum may receive a heating flue of any approved construction and in this manner it will be understood that when the stove 80 is in use a number of rooms may be heated through the provision of such flue. The top of the drum is provided with a removable closure 15 in which is formed a suitable number of passages 16 which are adapted 85 to be closed by the wings of a revolubly mounted damper 17.

The base member 1 is provided on its interior surface with a horizontally disposed flange 18 against which is seated the horizontally disposed flanged portion 19 of a fire pot 20. The sides of this fire pot, also the bottom are slotted, as shown, and the bars 21 on the bottom of the pot are formed with centrally alining grooves 22 for receiving the shank portion 23 of a grate 24. This grate is provided with horizontally disposed agitating fingers 25 which are interposed between the bars 21 of the fire pot. One end of the shank 23 of the grate extends through 90 a portion of the base member 1 where it may be conveniently manipulated by any approved shaking element, not shown.

A hopper 26 is located in the drum and disposed immediately above the fire pot. 105 This hopper also forms a permanent part of the stove and it is formed to provide an upper member consisting of a vertical wall 27 in which is formed a plurality of vertically disposed slots 28. The wall 27 of 110 the hopper is spaced from the walls of the drum to form a chamber 29. At the top of

the wall 27 is the outwardly flared wall 30 of the hopper and at the bottom of the said chamber is disposed a similar wall 31 of the hopper. The last named wall is connected 5 to the main body portion or wall 27 of the hopper by braces or legs 32 which are spaced from each other so that communication is established between the fire pot and the said chamber. The hopper 26 is provided with 10 base portion 33 which is adapted to rest upon the flange 19 of the fire pot. The base portion 33 and the wall 31 form the lower member of the hopper.

From the construction of the stove herein 15 set forth and described it will be readily understood by those skilled in the art that I employ as the main portion or base member a part which forms a permanent portion of the structure. The fire pot and the hopper described also form permanent parts of 20 the structure. The drum 10 referred to and shown forms what may be termed a detachable and non-permanent part, this being desirable in view of the fact that the said 25 drum will be made of sheet material which is desirable for the reason that in a wood burning stove it is essential to employ such metal that will heat readily and quickly. The drum 10 and the base member 1 form 30 in their entirety an inclosure or casing of a sectional structure and either of such parts may be replaced when worn by a new one at a minimum cost.

In operation of my improved stove, the 35 hopper is filled or partly filled with coal and as it is burned upon the grate the heat through the provision of the dampers described will tend to accumulate in the chamber 29 to heat such portions of the drum 40 which is disposed directly outwardly of the vertical walls of the hopper. In view of the formation of the slots or passages 28 in the hopper such small particles of coal that may fall through such passages will be deposited 45 upon the chute-forming portion 31 of the hopper so that such particles will be conveyed to the fire pot and prevented from accumulating in the chamber 29. The heated products when the stove is burning will 50 rise and be conveyed to the chamber by way of the passages which are formed between the legs 32.

The construction of the stove described

and set forth in the foregoing is such that when it is desired to use it as a wood burner 55 the drum can be first removed from the supporting base member, after which the firepot can be conveniently removed from the base member. The hopper is so constructed that it is spaced from the closure at the top 60 of the drum to form a chamber. It will be understood that the heat products in their escape from the fire-pot will be temporarily confined in the chamber 29, and incident to the provision of the slots 28 in the hopper, 65 the heat products will be free to escape after partial utilization or expenditure of its energy to pass through such fire-pot where it will be discharged to the chamber which, as described, is located between the top of 70 the fire-pot and the closure for the drum.

I claim:—

1. In a stove, the combination of a casing, a fire-pot, and grate suspended therein, and a hopper resting upon said fire-pot, said hopper comprising a base member and an upper member, legs connecting said members together in spaced relation to each other, each of said members being formed at its upper end with an outwardly flared wall forming 75 between said upper member and said casing a chamber, the vertical walls of said upper member being formed with vertical slots throughout substantially its entire circumference, substantially as described. 85

2. In a stove, the combination of a casing, a fire-pot, and grate suspended therein, and a hopper resting upon said fire-pot and removable from the casing, said hopper comprising a base member and an upper member, legs connecting said members together in spaced relation to each other, each of said members being formed at its upper end with an outwardly flared wall forming 90 between said upper member and said casing a 95 chamber, the vertical walls of said upper member being formed with vertical slots throughout substantially its entire circumference.

In testimony whereof I affix my signature 100 in presence of two witnesses.

ABRAM OSCAR HANCOCK.
